UNITED STATES PATENT OFFICE.

FRANCIS KARR, OF CHICAGO, ILLINOIS.

PILLOW-SHAM HOLDER.

SPECIFICATION forming part of Letters Patent No. 444,981, dated January 20, 1891.

Application filed March 3, 1890. Serial No. 342,330. (No model.)

To all whom it may concern:

Be it known that I, FRANCIS KARR, a citizen of the United States, and a resident of Chicago, county of Cook, and State of Illinois, have invented new and useful Improvements in Pillow-Sham Holders, of which the following is a specification, reference being had to the annexed drawings, two sheets, illustrating the invention, in which—

10 Figure 1, Sheet 1, is a face view of my invention in position on a bedstead properly to support pillow-shams; Fig. 2, a left-hand outside elevation of Fig. 1. Fig. 3, Sheet 2, is an elevation of the device removed from the 15 bedstead, extended and raised up; Fig. 4, an elevation of the right-hand end of the pillow-sham holder raised up and secured to the bed-post.

This invention relates to the novel construction of a main wire frame and the peculiar form of the wire lock by which the frame is held upon the bed-posts and its combination with a tilting frame which supports the pillow-shams, and so arranged as to be necessarily extended simultaneously with the main frame, and fabrics tightly wound spirally around two adjoining top wires of the tilting frame, whereby the pillow-shams may be properly and readily attached.

30 The nature of invention will be readily understood by the following detailed description: B represents one bracket by which one end of the main frame is held to the bed-post D, and C represents the bracket by which 35 the other end of the frame is held to the post D.

The main frame is composed of two wires, starting and continuing as follows: One end of the wire A is made to be a pivot in the free 40 end of the bracket B, and it is headed to hold the parts in place. Thence it passes through a loop a' of wire A' and forms a loop a around wire A'. Thence at b it forms a loop around wire A'; thence through loops h and h' of the 45 tilting frame and through loop b' of wire A'; thence through loop m of said tilting frame; thence returning to starting-point and forms a knot A'' around the wire A at the place of beginning. The other wire A' is made to be 50 a pivot in the free end of the bracket C, and

thence runs through a loop a of wire A and forms loop a' around wire A, extends to b' , and forms a loop around wire A; thence passes through loops h' and h of tilting frame, and also through loop b of wire A and through 55 loop m' of said tilting frame, and thence through loop c and returns to near the starting-point; then passes around itself and returns substantially parallel to itself, so as to form a loop c , and thence inward to form a 60 loop or coil d ; thence extends outward between the said parallel portions and terminates at c , and it thus forms a suitable spring to lock over the cam E on the free end of the bracket C and holds the two frames up, as 65 shown at Fig. 4. The tilting frame consists of two wires formed as follows: The wire F is spliced at its ends by loops r n or by other suitable means, and from one end it extends to p , where it is bent, as shown, and thence 70 through a loop g' of wire F', and then forms loop g ; thence to h , where it forms a loop around the wires A A' of the main frame; thence to i , where it forms a loop around the wire F'; thence through loop i' to j , where it 75 forms an eye; thence to m' , where it forms a loop around wire A of the main frame, and thence to the place of beginning. Wire F' of the tilting frame is a counterpart of the wire F in a reverse position and connected with 80 the other portions, as clearly shown in the drawings. From this it will be seen that the main frame is two-part in its nature, and can be extended one part on the other, and that the tilting frame, although hung to the main 85 frame, is also a two-part frame, which may be extended simultaneously with the main frame, whereby the extending of either frame will necessarily cause the other to be similarly extended. Tapes or suitable fabric 90 strips G and G' are respectively wound tightly and spirally around the wires F and F', and their ends are fastened to the eyes j j' , and at points O and O' on the respective two parts of the tilting frame, for the purpose of providing means for securing pillow-shams to the holder.

The advantages are simplicity, durability, cheapness of construction, and certainty of action.

I claim and desire to secure by Letters Patent—

In a pillow-sham holder made entirely of wire, the combination of a two-part extensible main frame, pivot and cam-brackets attached to the bedstead and supporting said frame, a two-part extensible tilting frame connected with the main frame, and eyes

formed integrally with said tilting frame and surrounding parts of said main frame, whereby both frames are extended by the extension of either, as specified.

FRANCIS KARR.
